Henry William Camp
Letters Patent

84504

The schedule referred to in these Letters Patent and making part of the same containing a description in the words of the said Henry William Camp himself of his improvement in the common Iron Cooking Stove.

To all to whom these presents shall come: Be it known that I Henry W. Camp of Owego in the County of Tioga and State of New York have invented a new and useful improvement in the construction and operation of the common Iron Cooking Stove; and that the following is a full and exact description of the construction and operation of the said stove as invented or improved by me, that is to say. The size and form of the stove is not so material and in that it may be varied. The following is a description of one of an ordinary size and shape with the proportions. The body of the stove being oblong has swelled sides and ends. The swelled or curved ends extend but part of the way from the top down, leaving the base or bottom part of the stove of much less dimensions than the upper part and has but two doors, one the fire door on the front side of the stove for putting in fuel, and the other the oven door on the backside of the stove. The body of the stove is twenty two inches and a half high and three feet in length across the top and about 22 inches wide including the projection for the reception of a boiler on the back side, the base or lower part being about 28 inches long and 14 inches wide through the centre and 9 through the ends, and has two hearths one on the front and one on the back side of the stove. The upper or fire hearth on the front side is sunk for holding ashes and coals, and the lower or oven hearth on the back side for the convenience of the oven which is in the lower part of the stove. The whole stove being an irregular figure a more perfect idea may be formed from the following description of the several plates and parts. 1st The bottom plate is a

Along figure with straight and parallel ends, curved or rounded corners and on the front side curved or twelled out 3 inches and straight on the back side, three feet long and two feet - 6 inches in width across the centre. On the top of which plate is a moulding three fourths of an inch high running ^{upright} around its outer edge and a like moulding runs out from the front moulding and distant about two inches from and within the outer end moulding and curves across the plate lengthwise so as to form with the front moulding an enclosed area about 25 inches long and nine inches wide at the ends and 16 in the centre of the curve for the reception of the upright plates which form the body of the stove. All of which mouldings are cast solid with the plate. Leaving the remainder of the plate projecting from under the body of the stove on the back side and at the ends so as to form a hearth for the oven about 10 inches wide before the oven door and 3 inches at the ends of the stove. The front edge of the plate and the moulding are ornamentally projected near the corners to form the bases of the pedestals. On the underside of which plate are ordinary brackets for fixing the cast iron legs which are about 14 inches long on which the stove stands. The side plates are two feet wide and twenty two inches high the front one of which curves or twells from one side to the other outwardly about 21 inches from a plane surface and has an opening in it above the middle of the plate and equidistant from the sides of the plate 16 inches long and 7 $\frac{1}{2}$ inches high for a door to the fire and through which the upper or fire hearth passes, irregularly formed on the under side to fit the bottom of the sink hearth which projects over and rests on it. The back side plate is curved in like manner about one and a half inches from a plane and has a like opening, 12 inches long and 7 inches high for a door to the oven and is equidistant from the sides and two and a half inches from the bottom plate or hearth, and two and a half inches above this door is a projection of this plate which at the top is of a circular form projecting five inches extending in this form from the top of the stove down 6 inches and then terminating in an oblique plane of 5 $\frac{1}{2}$ inches in length.

slanting into the body of the stove and terminating in one half inches above the top of the oven door forming an area within the stove for the reception of a boiler. These side plates have also several perpendicular and horizontal mouldings on their insides for the purpose of supporting several plates hereinafter described. These side plates have about two inches of the perpendicular edges curved or swelled out representing externally pilasters and forming hollows internally through which the binding rods pass from the top to the bottom plates and also forming grooves or shoulders within which the end plates are fitted. 3. The end plates are of the same height and are curved outwards in nearly a half circle extending from the top down $7\frac{1}{4}$ inches where about three inches of the projection terminates by the plates being scalloped or curved in and down three inches and then forming a pilaster surface which extends to the bottom plate about $11\frac{1}{4}$ inches. One of which end plates has an elliptical opening in it 9 inches in length and three inches in width placed horizontally and directly beneath the three inch curve or concave for the passage of the smoke and surrounded externally by a flange for the reception of a stove pipe. The top of this flange is about 9 inches from the top of the stove. Through the other end plate and on the hearth or bottom plate is a small aperture three inches by two for the purpose of clearing the fire under the oven and cooling the oven. 4th The top plate is so formed as to fit the side and end plates of the stove with a moulding on the under side around its outer edge projecting three fourths of an inch which binds all the upright plates together. This plate has four apertures of a circular form and nine inches diameter for the reception of boilers or other stove furniture which are covered with cast iron lids, and this plate and the moulding projects in four places in an ornament al form for the capitals of the pilasters. 5th The fire plate is a horizontal plate two feet long extending through the stove except the two inch spaces at the ends for the flues and is about equidistant from the bottom top plates and forms the top of the oven resting on a moulding in the back plate and also resting on the front plate through which

which it projects to form a hearth, and also on the upright end of the oven which are two inches from the end plates of the stone and together with the bottom plate of the oven form the flue which passes under the oven. This fire plate is $23\frac{1}{2}$ inches long and about 13 inches within the stone and at the distance of from $4\frac{1}{2}$ to 5 inches from the sides of the stone or edge of the plate it is sunk one and three quarters of an inch and projects thus the front plate fifteen inches, being six inches in width where it passes the front plate and forms a circular sunken hearth with a moulding extending around its outer edge. The sunken part of the hearth approaches within a half inch of the mouth except at the distance of five inches from the front plate where it ceases to two inches. A circular groove or shoulder runs around the upper edge of the sunken part $3\frac{1}{2}$ of an inch deep in which is fitted a plate which forms the upper side of the hearth and has a round hole in its centre to admit the air and a moulding one inch high on the top of its inner edge fitted for the purpose of closing the draught under the door and this plate may be partially or wholly removed at pleasure for the purpose of creating a draught or to use a gridiron. The sunken part of the plate within the stone is covered with a fire grate of a rectangular form fitted to cover it. The oven plate or plate which forms the bottom of the oven is four feet long and is two inches above and parallel with the bottom leaving a flue underneath it and extends to the side plates as to within two inches of the end plates joining the end plates of the oven and is supported by mouldings cast on the side plates. The two end plates of the oven are $10\frac{1}{2}$ inches long and $9\frac{1}{2}$ inches high and rectangular and are placed perpendicularly between oven plate and fire plate and meet the side plates and are supported by mouldings on the side plates near the grooves or pilasters. There are two perpendicular plates placed one on each end of the fire plate 4 inches high and extending across the width of the stone at the distance of five $\frac{1}{2}$ inches from the end plates the purpose of showing the fire upon the boiler and forming the

and protecting them from ashes, each plate having on its upper edge a horizontal grate cast solid on and forming with it a right angle, each of which grates extends towards the end plate in a conical form so as to cover the flues and protect the dampers from coals or fuel and these are held firmly in their places by mouldings cast on the side plates for that purpose. 9th. There are two flues or what is called a double flue. One is the long flue and extends over one of the plates last mentioned, passing through the grate and down between the end plate and this grates plate and still down between the end plate of the stove and that of the oven to the bottom plate, and passes under the oven and up on the other end of the stove between plates like those at the end where it passes down to the aperture where it passes off 8 $\frac{1}{4}$ inches from the bottom plate. And the other flue passes over the other upright plate and through its grate and down 4 $\frac{1}{4}$ inches directly to the aperture where it meets the long flue and both are discharged through the same into the pipe or chimney. 10th. There are two dampers formed of flat pieces of cast iron 9 inches by three extending at each end to form pivots and rounded at the corners and bevelled on one edge to fit and close the flue and rounded on the pivot edge for turning placed horizontally in the flues and resting on the ends of the fire plates with one pivot of each resting in countersinks in the front plate, and the others passing through the back side plate and made square so as to be turned on the outside with a small crank fitted to them for the purpose of closing either of the flues and regulating the draughts and for partially or wholly turning the fire under the oven or passing it off through the short flue and thus regulating the heat of the oven. The whole stove being bound together by four wrought iron rods passing through perpendicularly with heads in counter sink holes in the top plates and nuts on the rods beneath the bottom plate - the whole stove being of cast iron except the rods and turnings. The improvements claimed are principally as follows -

1st. In the form and construction of the flues & dampers for the fire place.

pose of directing and regulating the fire, being so constructed as to cause a draught of heat from the fire both ways and equalize turn it one way or the other by simply moving one or both dampers so as to apply the heat where it may be needed and turn under the oven or not or partially, so for baking with greater safety and better, the heat being by this process distributed equally if necessary through the whole stove and applied so directly by the bakers and cooking utensils or oven as to require less fuel and other differently constructed stove or fire place whatever, furnish the same facilities - all of which is further described.

2. In the form and construction of the fire hearth which is also described above, comprising an ordinary hearth on the top plate, ordinary use and convenience and a sunk hearth under it (as is said, with the sunk plate within the stove) contain convenient quantities of coals and ashes for cooking and forms a receptacle for ashes from the burning fuel which is upheld by the grate as described and by means of this and the draught made to burn fire and advantageously. This draught being caused and increased or diminished by means of a hole in the centre of the upper plate the hearth and the partial or entire removal of this plate, is removed entirely to admit of the use of a gridiron or other cooking utensil. 3. In the oven and the application of the heat to its location. It being so situated that it may have only gentle heat all around it or a heat on the upper side only, to intense heat all around it or otherwise, and which heat is shut off at once and cool air allowed to pass into the bottom.

4. In the situation of the main flue and flango for conducting the smoke in such a manner and placed as to ensure a draught admits of a beneficial use of the two flues and the dampers also mentioned. 5. In the formation and construction of the front plates which form the flues with the grates attached, to the whole of each being one piece cast a lid and forming an entire cover over the flues against the admission of fuel or other things.

114.

into the flues or out to the dampers without obstructing the draughts as further described above. 6th In the formation of the top plate and location of the four boilers in it so as to receive the heat from the fire on all of them equally. 7th The form and location of the fire grates over the sunk part of the plate within the stove, it being so placed as to admit of burning stone or charcoal and this too immediately under the boilers.
